UNITED STATES PATENT OFFICE.

MAX A. PURDY, OF WELLINGTON, KANSAS.

DISPLAY-STAND.

1,201,760.

Specification of Letters Patent.

Patented Oct. 17, 1916.

Application filed September 16, 1915. Serial No. 50,948.

To all whom it may concern:

Be it known that I, MAX A. PURDY, a citizen of the United States of America, residing at Wellington, in the county of Sumner and State of Kansas, have invented certain new and useful Improvements in Display-Stands, of which the following is a specification, reference being had to the accompanying drawings.

10 This invention relates to improvements in stands for displaying piece goods and garments such as waists, skirts, coats and the like; and an object of this invention is to provide a device of this character which 15 will be simple in construction, comparatively cheap in manufacture and efficient, durable and convenient in operation and use.

In the drawings illustrating the principle 20 of this invention and the best mode now known to me of applying that principle, Figure 1 is an elevation of my new display stand; Fig. 2 is a plan view of the body part thereof; Fig. 3 is a section on the line 3—3 of Fig. 2; Fig. 4 is a section on the 25 line 4—4 of Fig. 2; and Fig. 5 is a section on the line 5—5 of Fig. 3.

The body *a* is two-part. The part *a'* is formed at its top with a pair of oppositely-disposed, inwardly-projecting ribs *b*, *b''*, 30 and at its bottom with a pair of similar ribs *c*, *c''*. The part *a''* of the body *a* is likewise formed at its top with a pair of oppositely-disposed, inwardly-projecting ribs *b'*, *b''*, and at its bottom with a similar pair 35 of ribs *c'*, *c''*. The inner edges *d* of the upper ribs *b*, *b''* and the lower ribs *c*, *c''*, are hollow and are formed with substantially cylindrical guide-channels *e*. The inner edges *d'* of the upper ribs *b'*, *b''*, and the 40 lower ribs *c*, *c''*, carry guide-rods *e'* which fit slidingly in and are guided by the cylindrical guide-channels *e*. The parts *a'*, *a''*, of the body part *a* are formed with ribs *f*, *f'*, respectively; the rib *f* carries a screw-threaded 45 rod *g* and to the rib *f'* there is fastened a screw-threaded rod *g'*; these rods *g*, *g'*, are oppositely threaded and on them there is mounted, free to rotate, an interiorly-threaded sleeve *h* by the turning of which 50 the parts *a'*, *a''*, may be brought together

and moved from each other, as will be readily understood. On the sleeve *h* there is mounted a ring *i* from which extends a radial projection *j* that is formed with a socket *k* the inner wall of which is screw-threaded. The 55 ring *i* carries also a set-screw *m* the head of which is formed with a socket *n*; the inner wall of the latter is likewise screw-threaded. By tightening the set-screw *m*, the ring *i* may be held fast upon the sleeve *h*. An 60 annular rib *o* on the sleeve *h* serves to limit the movement of the ring *i* axially therealong. Into the threaded socket *k*, there is screwed one end of a rod *p* the other end of which is arranged to slide in a stand *q* having a base *r*. By tightening the set-screw *s*, the slide-rod *p* may be fastened in adjusted position. Into the socket *n*, there may be 65 screwed the lower end of a rod *t* on the upper end of which there is slidably fitted a T-post 70 *u*. By tightening the set-screw *s'*, the T-post *u* may be fastened in adjusted position.

By loosening the set-screw *m*, the sleeve *h* is made free to be turned within the ring *i* and thereby to move apart from or toward 75 each other the parts *a'*, *a''*, of the body *a*. It is obvious that these parts *a'*, *a''*, may be thus adjusted without in any way disturbing the rods *p*, *t*, or the parts within which these rods slide. A piece of material can be 80 draped over the T-post *u* and goods dropped on the inside of the form *a*, thereby making a unique display for use in salesrooms and the like. Of course, a waist and skirt may be displayed by means of my new stand, as 85 may also a coat or the like.

The simplicity and fewness of parts of my display stand are noteworthy.

I claim:

1. A display stand including a two-part 90 form; threaded rods carried by the parts of the latter; a threaded sleeve which engages both of said rods; a ring fastened on said sleeve for turning the same; a boss that projects from said ring; and a supporting 95 stand that is rigidly fastened to said boss.

2. A display stand including a two-part 100 form; threaded rods carried by the parts of the latter; a threaded sleeve which engages both of said rods; a ring mounted on said

sleeve; a fastening device for securing said ring to said sleeve; a display device supported by said fastening device; and a stand attached to said ring.

5 Signed at Wellington, in the county of Sumner and State of Kansas, this 9th day of

September, A. D. 1915, in the presence of the two undersigned witnesses.

MAX A. PURDY.
